UNITED STATES PATENT OFFICE.

GEORGES BERTHET AND VICTOR BERTHONNET, OF ST. JULIEN, NEAR TROYES, FRANCE,
ASSIGNORS TO STE. AME. DE BLANCHIMENT, TEINTURES, IMPRESSIONS ET APPRÉTS
DE ST. JULIEN, OF ST. JULIEN, NEAR TROYES, FRANCE.

FABRIC-PRINTING MACHINE.

No. 900,978.

Specification of Letters Patent.

Patented Oct. 13, 1908.

Application filed July 19, 1906. Serial No. 326,884.

To all whom it may concern:

Be it known that we, GEORGES BERTHET and VICTOR BERTHONNET, both citizens of the French Republic, and residents of St. 5 Julien, near Troyes, Aube, France, have jointly invented certain new and useful Improvements in Fabric-Printing Machines, of which the following is a specification.

This invention relates to certain improvements in machines such as are employed for printing ornamental or other designs upon fabrics and more particularly to such machines of this general class which are especially designed and adapted for printing such 10 designs or ornamentations upon tubular fabrics such, for example, as are employed in the manufacture of hosiery or the like, and the object of the invention is to provide a machine of this general character of a simple 15 and comparatively inexpensive nature having improved means for maintaining the tubular fabric in accurate position during the printing operation to the end that uniformity of the printed design may be assured 20 25 without rendering the printing operation unduly expensive.

The invention consists in certain novel features of the construction and combinations and arrangements of the several parts 30 of the improved fabric printing machine, whereby certain important advantages are attained and the machine is rendered simpler, less expensive and otherwise better adapted and more convenient for use, all as 35 will be hereinafter fully set forth.

The novel features of the invention will be carefully defined in the claims.

In the accompanying drawings which serve to illustrate our invention—Figure 1 is 40 a diagrammatic view of the machine embodying our improvements; Fig. 2 is a front view of the means for spreading the fabric, and Fig. 3 is a sectional detail view taken through the spreading means in the plane indicated by 45 the line $y-y$ in Fig. 2.

To avoid complexity due to unnecessary details of construction we have shown in Fig. 1 a somewhat diagrammatic representation of a fabric printing machine provided with 50 our improvements, wherein 1 designates the machine frame having suitable journal bearings for the support of the several rolls including the impression rolls 2 and 3 the two series of printing rolls 4, 4 and 5, 5, coacting

with the respective impression rolls for 55 printing the opposite surfaces of the fabric and the carrier rolls 6, 6 and 7, 7 over which are passed the aprons 8 and 9 for conveying the fabric through the improved machine.

The carrier rolls 6, 6 and the apron 8 supported thereby, are arranged at the upper part of the machine and serve to convey the fabric to be printed around the upper impression roll 2 so that one surface of the fabric may be printed by means of the printing rolls 60 4, 4 which coact with said impression roll 2 while the carrier rolls 7, 7 and the apron 9 supported thereby are arranged at the lower part of the machine and serve to convey the fabric after the same shall have been carried 65 around the upper impression roll 2 for the printing of one of its surfaces, and shall have been transferred to the lowermost impression roll 3, around said lowermost impression roll in order that the opposite surface of said fabric 70 75 may be printed by the operation of the corresponding printing rolls 5, 5 and thence out of the machine.

10 represents the tubular fabric during its course through the machine, there being 80 guide rolls 11, 11 at the upper and lower parts of the machine over which the said fabric is passed on being fed to and delivered from the machine. At the central part of the machine, this fabric travels in contact with the aprons 85 8 and 9, being so passed over the impression rolls that one of its faces is exposed to the printing surfaces of the rolls 4, 4, coacting with the upper impression roll, while its opposite surface is exposed to the printing surfaces 90 of the rolls 5, 5 coacting with the lower impression roll 3.

Above the uppermost impression roll 2 and arranged in the path of the tubular fabric 10 are arranged certain spreading means 12 95 adapted for entry within the tubular fabric so that the two plies thereof are caused to travel in front of and behind said spreading means as shown in Figs. 1 and 3, the construction of said spreading means being of such a nature 100 that the two plies of the tubular fabric are uniformly and tightly stretched and laid flat one upon the other at the instant of contact of the tubular fabric with the upper impression roll, so that the said fabric is caused to 105 be evenly stretched or laid upon the rolls 2 and 3, in order that the corresponding printing rolls may operate with accuracy to print

the opposite sides of the fabric. The said spreading means 12 as herein shown, comprise flattened plates 14, 14, extended parallel with each other and spaced apart as shown 5 in Fig. 2, in such a manner that their opposite or outer edges shall contact with the inner surface of the flattened tubular fabric at opposite sides thereof, in such a manner as to hold the same tightly strained in flattened 10 form at the instant the said fabric is being supplied to the bight of the upper impression roll 2 with the corresponding upper printing roll 4, the lower ends of said plates 14, 14 being loosely supported closely adjacent to the 15 bight of said rolls as shown in Fig. 1.

The plates 14, 14 are held at their upper ends upon frames 15, 15 from which the outer edge portions of said plates 14, 14 project, and said frames are provided, respectively, with 20 upper and lower tie or brace bars 16 and 17, which are extended between the respective frames and adjustably connected by loops or collars 18 and 19 so as to permit the tie or brace bars of one frame to slide lengthwise 25 upon the corresponding bars of the other frame in order that the plates 14, 14 may be adjusted to stand at different distances apart to accommodate the printing of tubular fabrics of different widths.

30 20 represents a screw shaft extended across the spreading means parallel with and beneath the lower tie or brace bars 17 and having its opposite ends reversely screw threaded and engaged in correspondingly screw threaded apertures in the respective collars 19, 19 each of which is secured to one of the respective tie or brace bars 17 which are embraced by said collars. By this construction it will be seen that the screw shaft 20 may be 35 turned in order to adjust the frames 15, 15 toward or from each other for accommodating the spreading means to tubular fabrics of different widths. Set screws 21, are provided upon the collars 19, 19 to permit of 40 locking the parts in relation when adjusted in position for use.

22, 22 represent spreading rollers arranged in pairs in front of and behind the respective frames 15, 15 and adapted to project in front 45 and behind said frames for engagement upon the inner surfaces of the plies of the tubular fabric in such a way as to separate said plies sufficiently, as shown in Figs. 1 and 3, to permit the said plies to travel past the spreading means without danger of catching upon or 50 wearing from contact with the upper parts of said spreading means.

23 represents a shaft extended across the machine in front of the fabric and above the 55 spreading means, the ends of said shaft being reversely screw threaded and carrying screw collars or nuts 24, 24 which, when the shaft is turned in one direction or the other, are caused to approach or recede from one another. Said collars or nuts 24, 24 are ar-

ranged at opposite sides of the path of the fabric and their peripheries are grooved out to receive hook like members 25, 25 which are secured to side frames 26, 26 which are braced by means of transverse bars or rods 70 27, 27 extended across the space between said frames in front of and behind the path of the fabric, the ends of said brace rods or bars 27, 27 being adjustably connected with the frames as clearly shown in Fig. 2. 75

28, 28 represent supporting rollers or members which are carried at their ends by the frames 26, 26 and are extended transversely across the space between said frames in front of and behind the spreading means. These 80 supporting rollers or members 28 are spaced apart from each other at a distance such that the front and rear plies of the fabric shall rest upon said rollers at points below the spreading rollers 2, 2 as shown in Figs. 1 and 3 so as 85 to effectively support the spreading device within the fabric without in any way interfering with the free movement of the fabric through the machine.

In order to prevent lateral displacement of 90 the fabric during its passage over the impression rolls, we provide guide rollers 29, 29 supported on studs carried by the plates 26, 26 said guide rollers having their peripheries arranged for contact upon the opposite edges 95 of the fabric outside the spreader plates 14, 14 in such a way as to press lightly and evenly upon the fabric. These rollers 29, 29 and the parts by which they are supported will, of course, require to be adjusted in position 100 corresponding with the adjustment of the parts of the spreading means.

In the operation of the improved machine, when the parts of the spreader and its supporting and retaining means shall have been 105 properly adjusted, the tubular fabric to be printed will be led down into the machine over the upper roller 11, the lower open end of said tubular fabric being passed over the spreading means in such a manner that said 110 spreading means are entirely inclosed within the fabric as shown in Figs. 1 and 3 and in broken lines in Fig. 2, whereby the plates 14, 14 are caused to maintain the two plies of the fabric tightly stretched and flattened in 115 proper position to receive the impression from the several printing rolls.

The lower ends of the plates 14, 14, being closely adjacent to the bight of the upper impression roll with its upper printing roll 4, 120 it is evident that said plates serve to guide the fabric to the point where it is gripped between said rolls and insures against any material variation in the width of the fabric as the same is laid upon the peripheries of the 125 impression rolls in position to be printed.

Having thus described our invention, what we claim and desire to secure by Letters Patent is:—

1. A machine of the character described 130

comprising fabric carrying and printing means in combination with a spreading device comprising adjustably connected parts oppositely arranged for engagement at opposite sides of and adapted to be inclosed within a tubular fabric for spreading the opposite sides of the fabric apart from each other.

2. A machine of the character described comprising fabric carrying and printing means, a spreading device adapted to be inclosed within a tubular fabric to spread the plies thereof, and rollers extended at opposite sides of the path of the tubular fabric and adapted for contact with the plies thereof to move said plies toward each other to maintain the inclosed spreading device in position within the tubular fabric.

3. A machine of the character described comprising fabric carrying and printing means, a spreading device adapted to be inclosed within a tubular fabric and having spaced rollers adapted for contact upon opposite sides of the tubular fabric to spread the plies thereof, away from each other, and supporting means comprising parts arranged for contact with opposite sides of the tubular fabric to move the plies thereof toward each other to maintain the spreading device inclosed in the tubular fabric in position.

4. A machine of the character described comprising fabric carrying and printing means, a flattened spreading device adapted to be inclosed within a tubular fabric and arranged in relation to said fabric carrying and printing means with opposite edge portions adapted to bear at opposite sides of the fabric to spread the same in two flattened plies, and parts arranged for engagement at the opposite edges of the fabric outside the edge portions of the flattened spreading device to hold the fabric against displacement.

5. A machine of the character described comprising fabric carrying and printing means, a flattened spreading device adapted to be inclosed within a tubular fabric and arranged in relation to said fabric carrying and printing means with opposite edge portions adapted to bear at opposite sides of the fabric to spread the same in two flattened plies, and rollers arranged for engagement at the opposite edges of the fabric outside the edge portions of the flattened spreading device to hold the fabric against displacement.

6. A machine of the character described comprising fabric carrying and printing means, and a spreading device adapted to be inclosed within a tubular fabric and arranged in relation to said fabric carrying and printing means and comprising adjustably connected flattened plates the outer edge portions of which are adapted to be engaged at opposite sides of the tubular fabric to spread the same in flattened form.

7. A machine of the character described

comprising fabric carrying and printing means, a flattened spreading device adapted to be inclosed within a tubular fabric to spread the same in two plies and having opposite flattened surfaces adapted for contact with such plies of said tubular fabric, and supporting means comprising parts arranged for contact with the outer surfaces of such plies of said tubular fabric and extended parallel with the opposite flattened surfaces of said spreading device and adapted to move such plies of said tubular fabric toward each other to maintain the spreading device in position within said tubular fabric.

8. A machine of the character described comprising fabric carrying and printing means, a flattened spreading device adapted to be inclosed within a tubular fabric to spread the same in two plies and having opposite flattened surfaces adapted for contact with such plies of said tubular fabric, and rollers extended parallel with the opposite flattened surfaces of said spreading device and adapted for contact with the plies of said tubular fabric to move such plies toward each other to maintain the spreading device in position within said tubular fabric.

9. A machine of the character described comprising fabric carrying and printing means, a flattened spreading device adapted to be inclosed within a tubular fabric to spread the same in two plies and having opposite flattened surfaces adapted for contact with such plies of said tubular fabric, supporting means comprising spaced parts parallel with said opposite flattened surfaces of the spreading device and adapted for contact with the outer surfaces of said plies of the tubular fabric to move such plies toward each other to maintain the spreading device in position within such tubular fabric, and other parts extended in the space between said supporting parts and adapted for engagement with the outer surface of the tubular fabric at opposite edges of the flattened spreading device to hold the fabric against displacement.

10. A machine of the character described comprising fabric carrying and printing means, a flattened spreading device adapted to be inclosed within a tubular fabric to spread the same in two plies and having opposite flattened surfaces adapted for contact with such plies of said tubular fabric, supporting means comprising spaced parts parallel with said opposite flattened surfaces of the spreading device and adapted for contact with the outer surfaces of said plies of the tubular fabric to move such plies toward each other to maintain the spreading device in position within such tubular fabric, and other parts extended in the space between said supporting parts and adjustable toward and from each other and adapted for engagement with the outer surface of the tubular fabric

at opposite edges of the flattened spreading device to hold the fabric against displacement.

11. A machine of the character described comprising fabric carrying and printing means, a flattened spreading device adapted to be inclosed within a tubular fabric to spread the same in two plies and having opposite flattened surfaces adapted for contact with such plies of said tubular fabric, supporting means comprising spaced parts parallel with said opposite flattened surfaces of the spreading device and adapted for contact with the outer surfaces of said plies of the tubular fabric to move such plies toward each other to maintain the spreading device in position within said tubular fabric, and rollers extended in the space between said supporting parts and adapted for engagement with the outer surface of the tubular fabric at opposite edges of the flattened spreading device to hold the fabric against displacement.

12. A machine of the character described comprising fabric carrying and printing means, a flattened spreading device adapted to be inclosed within the tubular fabric to spread the same in two plies and having opposite flattened surfaces adapted for contact with such plies of said tubular fabric, supporting means comprising spaced parts parallel with said opposite flattened surfaces of the spreading device and adapted for contact with the outer surfaces of said plies of the tubular fabric to move such plies toward each other to maintain the spreading device in position within said tubular fabric, and rollers extended in the space between said supporting parts and adjustable toward and from each other and adapted for engagement with the outer surface of the tubular fabric at opposite edges of the flattened spreading device to hold the fabric against displacement.

13. A machine of the character described comprising fabric carrying and printing means, a spreading device adapted to be inclosed within a tubular fabric and arranged in relation to said fabric carrying and printing means and comprising adjustably connected flattened parts the outer edges of which are adapted to be engaged at opposite sides of the tubular fabric to spread the same in two flattened plies, and parts arranged for engagement with the outer surface of the tubular fabric opposite to the outer edges of the respective parts of said spreading device to hold the fabric against displacement.

14. A machine of the character described comprising fabric carrying and printing means, a spreading device adapted to be inclosed within a tubular fabric and arranged in relation to the fabric carrying and printing means and comprising adjustably connected flattened parts the outer edges of

which are adapted to be engaged at opposite sides of the tubular fabric to spread the same in two flattened plies, and parts adjustable toward and from each other and arranged for engagement with the outer surface of the tubular fabric opposite to the outer edges of the respective parts of said spreading device to hold the fabric against displacement.

15. A machine of the character described comprising fabric carrying and printing means, a spreading device adapted to be inclosed within a tubular fabric and arranged in relation to the fabric carrying and printing means and comprising adjustably connected flattened parts the outer edges of which are adapted to be engaged at opposite sides of the tubular fabric to spread the same in two flattened plies, and rollers arranged for engagement with the outer surface of the tubular fabric opposite to the outer edges of the respective parts of said spreading device to hold said fabric against displacement.

16. A machine of the character described comprising fabric carrying and printing means, a spreading device adapted to be inclosed within a tubular fabric and arranged in relation to the fabric carrying and printing means and comprising adjustably connected flattened parts the outer edges of which are adapted to be engaged at opposite sides of the tubular fabric to spread the same in two flattened plies, and rollers adjustable toward and from each other and arranged for engagement with the outer surface of the tubular fabric opposite to the outer edges of the respective flattened parts of said spreading device to hold the fabric against displacement.

17. A machine of the character described comprising fabric carrying and printing means, a flattened spreading device adapted to be inclosed within a tubular fabric to spread the same in two plies and having opposite flattened surfaces adapted for contact with such plies of said tubular fabric, supporting means comprising spaced rollers parallel with said opposite flattened surfaces of the spreading device and adapted for contact with the outer surfaces of said plies of the tubular fabric to move such plies toward each other to maintain the spreading device in position within such tubular fabric, and parts extended in the space between said supporting rollers and adapted for engagement with the outer surface of the tubular fabric at opposite edges of the flattened spreading device to hold the fabric against displacement.

18. A machine of the character described comprising fabric carrying and printing means, a flattened spreading device adapted to be inclosed within a tubular fabric to spread the same in two plies and having opposite flattened surfaces adapted for contact with such plies of said tubular fabric, sup-

porting means comprising spaced rollers parallel with said opposite flattened surfaces of the spreading device and adapted for contact with the outer surfaces of said plies of the 5 tubular fabric to move such plies toward each other to maintain the spreading device in position within such tubular fabric, and parts extended in the space between said supporting rollers and adjustable toward and from 10 each other and adapted for engagement with the outer surface of the tubular fabric at opposite edges of the flattened spreading device to hold the fabric against displacement.

19. A machine of the character described 15 comprising fabric carrying and printing means, a flattened spreading device adapted to be inclosed within a tubular fabric to spread the same in two plies and having opposite flattened surfaces adapted for contact with such 20 plies of said tubular fabric, supporting means comprising spaced rollers parallel with said opposite flattened surfaces of the spreading device and adapted for contact with the outer surfaces of said plies of the tubular fabric to 25 move such plies toward each other to maintain the spreading device in position within such tubular fabric, and other rollers extended in the space between the first-mentioned rollers and adapted for engagement with the outer 30 surface of the tubular fabric at opposite edge

of the flattened spreading device to hold the fabric against displacement.

20. A machine of the character described comprising fabric carrying and printing means, a flattened spreading device adapted 35 to be inclosed within a tubular fabric to spread the same in two plies and having opposite flattened surfaces adapted for contact with such plies of said tubular fabric, supporting means comprising spaced rollers parallel with 40 said opposite flattened surfaces of the spreading device and adapted for contact with the outer surfaces of said plies of the tubular fabric to move such plies toward each other to maintain the spreading device in position 45 within such tubular fabric, and other rollers extended in the space between the first-mentioned rollers and adjustable toward and from each other and adapted for engagement with the outer surface of the tubular fabric at opposite 50 edges of the flattened spreading device to hold the fabric against displacement.

In witness whereof we have hereunto signed our names this 2 day of July 1906, in the presence of two subscribing witnesses. 55
